UNITED STATES PATENT OFFICE

151,602

DESIGN FOR A GAME BOARD

Carl V. De Mattio, Rockford, Ill.

Application January 9, 1947, Serial No. 136,016

Term of patent 14 years

(Cl. D34—5)

To all whom it may concern:

Be it known that I, Carl V. De Mattio, a citizen of the United States, residing at Rockford, in the county of Winnebago and State of Illinois, have invented a new, original, and ornamental Design for a Game Board, of which the following is a specification, reference being had to the accompanying drawing, forming part thereof.

In the drawing:

Figure 1 is a top face view of a game board showing my new design, the opposite side thereof being plain, and the different shaded portions thereon indicating contrasting colors, and

Figure 2 is an edge view of the board, the opposite edges being plain and of the same thickness.

I claim:

The ornamental design for a game board, substantially as shown and described.

CARL V. DE MATTIO.
